UNITED STATES PATENT OFFICE.

OSCAR D. KLEINSTEUBER, OF MILWAUKEE, WISCONSIN, ASSIGNOR TO ALEXANDER L. DOELGER, OF MILWAUKEE, WISCONSIN.

MUNICIPAL-SERVICE POST.

1,165,420.

Specification of Letters Patent. Patented Dec. 28, 1915.

Application filed October 30, 1914. Serial No. 869,393.

To all whom it may concern:

Be it known that I, OSCAR D. KLEINSTEUBER, a citizen of the United States, and resident of Milwaukee, in the county of Milwaukee and State of Wisconsin, have invented certain new and useful Improvements in Municipal-Service Posts; and I do hereby declare that the following is a full, clear, and exact description thereof.

My invention consists in what is herein particularly set forth with reference to the accompanying drawings and pointed out in the claims of this specification, its object being to provide economical all metal municipal service posts of advantageous construction by which to facilitate their erection and handling, as well as access to hollow sections of the same; one of said sections of each post being preferably organized for the installation therein of separately accessible fire-alarm apparatus, police signal and telephone apparatus, and telephone apparatus for the use of municipal officials and employees in general.

Figures 1 and 2 of the drawings are respectively indicated by lines 1—1 and 2—2 in Fig. 3, and each represents a half sectional side elevation of one of my improved municipal service boxes; Figs. 3 and 4 represent horizontal sectional views respectively indicated by lines 3—3 and 4—4 in Fig. 1; Fig. 5, represents a similar view indicated by line 5—5 in Fig. 2, and Fig. 6, represents a sectional view of a detail of the post indicated by line 6—6 in Figs. 2 and 5.

All the matching sections of the herein described post are of cast-metal, four sided and hollow, their general exterior ornamental contour being variable without departure from what is claimed.

Referring by numerals to the drawings, 7 indicates the base-section, 8 and 9 shaft-sections, 10 a box-section, and 11 the cap-section of the post.

The base has an upper inset horizontal shoulder 12 upon which to stand the lower shaft-section 8 and this shaft-section is fastened by screws 13 to a vertical upper flange 14 of the base, the joint being weather-tight. A portion of one side of the base and of the shaft-section 8 is a removable panel 15 that sets in against vertical facing flanges 16 adjacent to an opening in said base and shaft sections to exclude moisture. The

panel 15 is provided with lower inner hooks 55 17 that pass through interruptions 18 of the flanges 16 and catch on said flanges, as is best shown in Figs. 1 and 6, the upper end of said panel being fastened by a screw 19 against a facing flange 20 in the shaft-section 8. To facilitate manipulation of said panel, the same is provided with an outwardly open socket 21 in which to engage the hand of an operator.

The upper end of the shaft-section 8 abuts 65 a continuous horizontal flange 22 in the upper shaft-section 9, the joint of the two shaft-sections being weather-tight, and said shaft-sections are suitably fastened together, the fastening means shown being screws 23 70 extending through inner ears 24 and the flange 22 of the shaft-section 9 into walls of the shaft-section 8.

The box-section 10 is set on the upper shaft-section 9, the joint being weather-tight, and the two are suitably fastened together, the fastening means shown being screws 25 extending through a continuous horizontal inner flange 26 of the box into ears 27 of said shaft-section. Three sides of 80 the box are shown open, and the openings are closed by doors 28, 29, 30, in hinge-connection with said box and provided with locks 28', 29' and 30', respectively. Over each opening, the box is provided with a 85 weather shedding hood 31 that is shown held in place by screws 32, and each door closes weather-tight in a wall depression of said box.

Set on the upper end of the box 10 is 90 the cap 11, the joint being weather-tight, and screws 33 are shown as means for fastening said cap in place. The apex of the cap is provided with a socket in which to secure (by screw-threading or otherwise) the 95 shank of an ornament 34 or a signal fixture, such fixtures having been employed in connection with municipal service posts.

The box 10 is shown provided with upper and lower parallel webs 35 crossing said box 100 in one direction central of the same, and each web is provided with a central vertical rib 36 and with a vertical flange 37 at a terminal of the rib. A fire-alarm box 38 is fastened to the flanges 37 of the webs 35 105 to be accessible through a doorway in the box 10 of the post, and opposite backings 38, for the support of signal and telephone

apparatus, are held in place within said box 10 by bolting through the ribs 36 of the same, a set of bolts 39 with washers and nuts thereon being shown in Fig. 1.

5 One of the backings 38' in the post-box 10 is designed for the support of telephone and signal apparatus for the exclusive use of a municipal police force, and the other of said backings is intended for the support of 10 phone apparatus for the use of various municipal officials and employees to communicate with various municipal departments through a suitably located central station, access to the fire-alarm, police service 15 and general service apparatus being had through different doorways of said post-box.

The several sections of the post are light enough to be easily handled by two men, 20 and this facilitates erecting and taking down of said post with the least possible expenditure of time and labor.

By removing of the shaft-panel 15 of the post, ready access is had to electric terminal 25 connections in said post, and the removal of said panel may be easily accomplished by a single inspector or repairer, whereby time and labor are economized. The panel having been removed and electrical connections 30 broken, the post and its contents may be readily moved off its site to permit of uncovering electric conductor conduits or other work about said site, the moving of said post being easily accomplished by two men, 35 whereas a gang of men is required to remove an ordinary intact municipal service post from its site.

It will be observed that the shaft section 8 has its upper end telescopically connected 40 with the depending base portion of the connecting section 9, and that said connecting

section 9 has its upper end telescopically connected with the depending base portion of the box section 10. Such connections are made rigid by means of the screws 23 and 45 25 and the flanges 22 and 26. This manner of connecting the sections is a weatherproof one, and also permits the sections to be readily separated by releasing the screws 23 and 25. 50

I claim:

1. A municipal signaling station formed in sections one a section thereof provided with inner upper and lower horizontal webs each provided with a vertical rib and with a vertical flange at a terminal of the rib, a fire-alarm box fastened to said flanges, bolts extending through said ribs, and opposite backings of telephone and signal apparatus fastened on the bolts, the fire-alarm box and other apparatuses being accessible through separate openings in the section for which closures are provided. 60

2. A structure of the class described comprising a plurality of superimposed hollow sections the uppermost of which forms a receiving compartment and is provided with door openings, doors for said openings and means disposed in the interiors of the sections for locking their meeting ends together whereby the sections may be disconnected only upon access being had through said compartment doors. 65

In testimony that I claim the foregoing I have hereunto set my hand, at Milwaukee, 70 in the county of Milwaukee and State of Wisconsin, in the presence of two witnesses.

OSCAR D. KLEINSTEUBER.
